UNITED STATES PATENT OFFICE.

WILLIAM OTHO REID, OF STRAWN, TEXAS.

CUT-OFF LOCK.

1,211,756.

Specification of Letters Patent.

Patented Jan. 9, 1917.

Application filed July 29, 1915, Serial No. 42,567. Renewed July 13, 1916. Serial No. 109,195.

To all whom it may concern:

Be it known that I, WILLIAM OTHO REID, a citizen of the United States, residing at Strawn, in the county of Palo Pinto and State of Texas, have invented certain new and useful Improvements in Cut-Off Locks, of which the following is a specification.

The present invention relates to a gasoline cutoff for motor vehicles, and has for its object to provide a device of this character which embodies novel features of construction whereby the flow of gasoline from the tank to the carburetor is controlled by a lock mechanism so that the vehicle can be left standing without danger of being stolen or used by an unauthorized person.

Further objects of the invention are to provide a cut-off mechanism of this character which can be readily interposed between the gasoline tank and the carburetor and mounted upon any conventional construction of car, which is comparatively simple and inexpensive in its construction, which can be quickly locked or unlocked, and which 25 when in a locked position completely cuts off the supply of gasoline to the carburetor so that it is impossible to move the car under its own power.

With these and other objects in view, the invention consists in certain novel combinations and arrangements of the parts as will more fully appear as the description proceeds, the novel features thereof being pointed out in the appended claims.

For a full understanding of the invention, reference is to be had to the following description and accompanying drawing, in which:—

Figure 1 is a fragmentary longitudinal sectional view through an automobile, showing the gasoline cut-off lock applied thereto in side elevation. Fig. 2 is a transverse sectional view through the valve and lock box, taken on the line 2—2 of Fig. 1. Fig. 3 is a longitudinal sectional view through the valve.

Corresponding and like parts are referred to in the following description and indicated in all the views of the drawing by the same reference characters.

Specifically describing the present embodiment of the invention, the numeral 1 designates a gasoline tank which has the usual sediment bulb 2 at the bottom thereof, and from which gasoline is fed to the carburetor 3 through a supply pipe 4. Interposed in

the length of the supply pipe 4 at a convenient position is the casing 5 of a cut-off valve. The inlet end 5^a of the valve casing 5 is in communication with the gasoline tank, 60 while the outlet end 5^b thereof is in communication with the carburetor. The interior of the valve casing is formed with a tapered or wedge shaped valve chamber 6 arranged at right angles to the passage through the valve casing and communicating with the inlet and outlet openings thereof. A tapered valve 7 is mounted to reciprocate within the valve chamber 6 and has a shape corresponding to that of the valve chamber. 70 When the valve is moved upwardly so as to be seated against the walls of the valve chamber the inlet and outlet openings of the valve casing are closed and the flow of gasoline through the valve shut off. The bottom 75 of the valve casing 5 is formed with a drain opening which is normally closed by a removable plug 8, and a coil spring 9 is interposed between the removable plug and the valve 7 for normally holding the latter in a 80 closed position. A cap 10 is threaded in the top of the casing 5 so as to close the same, said cap being formed with a tubular standard 11 which projects upwardly therefrom. A valve stem 12 extends through the tubular 85 standard 11 and has the lower end thereof connected to the valve 7. This valve stem 12 passes through a packing ring 14 arranged within the tubular standard 11 and has a tight joint therewith so that there will be 90 no leakage above the packing ring. The upper end of the valve stem 12 has a collar or washer member 15 at the upper end thereof, and a coil spring 16 which surrounds the valve stem is interposed between the said 95 collar and the packing ring 14. This spring 16 co-operates with the before mentioned spring 9 to hold the valve 7 yieldably in a closed position. When it is desired to remove the valve 7 for any purpose, the collar 100 15 is detached from the upper end of the valve stem 12 and the plug 8 unscrewed from the opening in the bottom of the valve casing. The valve 7 and valve stem 12 can then be readily withdrawn through the bottom 105 of the valve casing.

Mounted in a suitable position upon the dashboard or instrument board of the vehicle is a lock box or casing 17. A packing box 18 projects downwardly from the bottom of the lock box 17 at the point toward one end thereof, and a plunger 19 extends

through the packing box. The upper end of the plunger 19 terminates in a head 20, while the lower end thereof projects into the upper end of the tubular standard 11 so as to engage the valve stem 12 when the plunger is depressed. A gland 21 is shown as fitted in the upper end of the packing box 18, and a coil spring 22 is interposed between the gland and the head 20 so as to normally hold the plunger in an elevated and inoperative position. The valve 7 is normally held in a closed position by the combined action of the coil springs 9 and 16, although when the plunger 19 is forced downwardly against the action of the spring 22, the valve 7 is moved downwardly into an open position. Communication between the gasoline tank and the carburetor is then unobstructed so that the engine will receive a continuous supply of the combustible mixture after being started.

An operating lever 23 is pivotally mounted within the lock box 17, one end of the said lever being hinged at 24 to the bottom 25 of the lock box, while the opposite end thereof is inclined upwardly toward the top of the lock box, and rests upon the head 20 at the top of the plunger 19. A locking slide 25 extends through one end of the lock box 17, the inner end thereof being provided at the top thereof with a roller 26 for engagement with the top of the lock box 17, and at the bottom thereof with a roller 27 for engagement with the operating lever 23. The locking slide moves in a position parallel to the top of the lock box 17 and at an angle to the lever 23, so that when the locking slide is forced inwardly the roller 27 swings the operating lever 23 downwardly and depresses 40 the plunger 19 so as to open the cut-off valve. However, when the locking slide 25 is moved outwardly the operating lever 23 is released and the plunger 19 moved upwardly by the action of the spring 22, the cut-off valve 7 being simultaneously seated by the combined action of the springs 9 and 16.

A suitable lever 28 may be provided upon the exterior of the lock box 17 for convenience in manipulating the locking slide 25, the said lever being shown as having a pin and slot connection 29 with the outer end of the said locking slide. It will also be observed that the locking slide is formed with a pair of notches 30 which are adapted to 55 operate with the bolt 31 of a key controlled lock 32 for the purpose of locking the slide in either an operative or an inoperative position. When the motor vehicle is in use the slide 25 is pushed inwardly so as to open the 60 cut-off valve 7 and lock it in an operative position. However, when the motor vehicle is not in use, or it is desired to leave the same standing, the slide 25 is pulled outwardly and locked in an inoperative position. The 65 cut-off valve 7 is then closed by the combined

action of the springs 9 and 16, so that there is no flow of gasoline from the tank to the carburetor, and the vehicle can not be moved under its own power. The lock box or casing 17 can be placed in any convenient position upon the dashboard of the vehicle, and it is impossible to tamper with the cut-off or change the adjustment thereof without the proper key for operating the lock 32. After the mechanism has been set to leave the cut-off valve in a closed position, the vehicle can be left standing without danger of being stolen or used by joy-riders, and it is impossible to change the adjustment without the proper key for manipulating the lock 32.

Having thus described the invention, what I claim as new and desire to secure by Letters Patent, is:—

1. A gasoline cut-off for internal combustion engines, including a cut-off valve interposed between the gasoline tank and the carburetor, a plunger, an operative connection between the plunger and the cut-off valve, an inclined lever pivoted at one end thereof, the free end of the inclined lever engaging the plunger, a locking slide coöperating with the inclined lever to control the plunger, and means for holding the locking slide in adjusted positions.

2. A gasoline cut-off for internal combustion engines, including a cut-off valve interposed between the gasoline tank and the carburetor, a lock box, a plunger projecting into the lock box, an operative connection between the plunger and the cut-off valve, an inclined lever engaging the plunger, a locking slide mounted within the lock box and coöperating with the inclined lever to control the plunger, and means for holding the locking slide in adjusted positions.

3. A gasoline cut-off for internal combustion engines, including a cut-off valve interposed between the gasoline tank and the carburetor, a lock box, a plunger projecting into the lock box and having an operative connection with the cut-off valve, an inclined lever arranged within the lock box and engaging the plunger, a locking slide mounted within the lock box and provided with anti-friction rollers engaging an interior wall of the lock box and the inclined lever so that by manipulating the operating slide the lever can be moved to control the plunger, and means for holding the locking slide in adjusted positions.

4. A gasoline cut-off for internal combustion engines, including a valve casing interposed between the gasoline tank and the carburetor, a reciprocating cut-off valve mounted within the valve casing, a tubular standard projecting from the valve casing, a valve stem connected to the valve and extending loosely through the tubular standard, a spring normally holding the valve in a closed position, a plunger mounted in alignment

with the valve stem and adapted to engage the same to open the valve, a swinging lever engaging the plunger, a locking slide mounted for coöperation with the swinging lever 5 to control the plunger, and means for holding the locking slide in adjusted positions.

5. A gasoline cut-off for internal combustion engines, including a valve casing interposed between the gasoline tank and the carburetor, a reciprocating cut-off valve mounted within the valve casing, a tubular standard projecting from the valve casing, a valve stem connected to the valve and passing loosely through the tubular standard, a packing ring arranged within the tubular standard and tightly engaging the valve stem, a collar upon the valve stem, a spring interposed between the collar and the packing 10

ring and normally holding the valve in a closed position, a lock box, a plunger projecting into the lock box and arranged in alignment with the valve stem so as to engage the same to open the valve, an inclined lever engaging the plunger, a locking slide mounted to move at an angle to the inclined lever, a roller upon the locking slide for engagement with the inclined lever to move the same and control the plunger, and means for holding the locking slide in adjusted positions. 20 25

In testimony whereof I affix my signature in the presence of two witnesses.

WILLIAM OTHO REID.
